TOP FOR ELECTROLYTIC CELLS OF THE
TANK TYPE

Donald W. Kent, Whitemarsh, Pa.

Application November 1, 1945, Serial No. 626,006

6 Claims. (Cl. 204—266)

1

This invention is a new and useful top for an electrolytic cell of the tank type and will be fully understood from the following description read in conjunction with the drawings, in which:

Fig. 1 is a plan view of part of an electrolytic cell provided with a top of my invention;

Fig. 2 is an end view with a part in section of the construction shown in Fig. 1;

Fig. 3 is a side view of certain elements of the construction shown in Fig. 1;

Fig. 4 is a side view of a sub-assembly of elements of the construction shown in Fig. 1;

Fig. 5 is a side view of other elements of the construction shown in Fig. 1;

Fig. 6 is another sub-assembly of elements of the construction shown in Fig. 1;

Fig. 7 is a top view of an element of the construction shown in Fig. 1;

Fig. 8 is an end view of the construction shown in Fig. 7, and

Fig. 9 is a side view of part of the construction shown in Figs. 7 and 8.

In the drawings, 1 designates the tank within which the electrodes and the electrolyte are contained. As indicated in Fig. 1, the cell top 2 consists of a large number of laminations or strips of which 3—27 appear in Fig. 1 held securely together by stay bolts 28, 29 and 30. The positive electrodes are provided with terminals 31—36 inc., which project up through top 2 and the negative electrodes are provided with terminals 41—46 inc., which similarly project up through the top.

In Fig. 3, I have shown a detailed side view of strip 10 which is identical in form with strip 22. Strip 10 defines part of the hole 51 through which the stay bolt 28 passes and part of hole 52 through which the stay bolt 29 passes. It also defines one side of the space 53 through which the electrode terminal 32 extends upwardly and a part of the horizontal duct or manifold 54 which extends through the strips or laminations within top 2 as shown in Fig. 1. The particular type of cell shown is adapted to produce gases such as hydrogen and oxygen by electrolysis of an aqueous electrolyte, and the function of manifold 54 is to carry off the oxygen or similar gas liberated at the positive electrode, and for this purpose it is provided at intervals with outlets such as 55 (Figs. 3 and 4) and 56 (Fig. 1).

For the purpose of admitting the oxygen into the manifold 54, the strip 10 also defines half of the riser 62 and such risers 61—66 (Fig. 1) are provided in the pairs of strips 5—6, 9—10, 13—14, 17—18, 21—22 and 25—26 which are as-

2

sociated with the positive electrodes. Each of these pairs of strips is identical except that pairs 9—10 and 21—22 additionally carry outlets 55 and 56.

Each positive electrode such as 70 (Fig. 3) is supported by a suspension bolt such as 71 (Fig. 3) provided at its lower end with a U-bar 72 to which the electrode is secured and at its upper end by a cap nut 73 by which bolt 71 is held in position in top 2. The strip 10 cooperates with a mating strip 9 (Fig. 4) which is a mirror image of the strip 10 and which defines the other half of space 53 and carries the other half of outlet 55.

Each positive electrode is surrounded by a diaphragm which may, for example, be formed of woven asbestos cloth and means is provided for supporting this diaphragm in spaced relationship to the electrode which means will now be described.

The diaphragm holder 81 with the diaphragm 82 depending therefrom is shown in side view in Fig. 4. The diaphragm holder (Fig. 7) is formed of two pieces 83 and 84 of thin sheet metal such as nickel. Part of the ends of the two flat pieces 83 and 84 (Figs. 7 and 9) are bent inwardly to form the overlapping ends or tabs 85 and 86 which may be spot-welded together or similarly secured. The opposite end of holder 81, which does not appear in the figure, is of similar construction. Adjacent either end and at the upper edge of bent-over portions 85 and 86 there is provided a small angle such as 87 which is riveted to the bent-over portions 85 and 86 and defines the holes 88 and 89 (Fig. 7) through which small machine screws such as 90 (Fig. 9) may be inserted to hold the diaphragm holder 81 up against the strips 9 and 10 (Fig. 4).

The diaphragm 82 (Fig. 4) which surrounds the positive electrode 70 operates to retain any gas such as oxygen liberated at the face of this electrode diverting it upwardly through riser 62 into the horizontal manifold 54 and thence out through the ducts such as 55 and 56 (Figs. 1 and 3). A diaphragm holder and diaphragm supported thereby are used in association with each of the pairs of strips 5—6, 9—10, 13—14, 17—18, 21—22, 25—26 and the positive electrode carried thereby.

It is not necessary to provide the negative electrodes with diaphragms and the construction of the negative electrodes with that part of the cell top pertaining thereto is shown in Figs. 5 and 6. In this case, negative electrode 101 is carried by the U-bar 102 secured to suspension bolt

103 which in turn is provided with cap nut 104 resting on strips 11 and 12 of which 12 appears in Fig. 5 and both 11 and 12 in Fig. 6. Strip 12 (Fig. 5) defines half of space 107 through which electrode terminal 42 projects upwardly and part of the horizontal manifold 108 (Figs. 1 and 5). Each manifold is provided at intervals with outlets such as 109 (Fig. 5) and 110 (Fig. 1) by which gas may be withdrawn from manifold 108. Strips 11 and 12 together define riser 112 by which any gas evolved at the face of the negative electrode will pass upwardly into the manifold 108 from which it can be withdrawn through outlets 109 and 110. Such risers 111—116 are correspondingly provided in the pairs of strips 7—8, 15—16, 19—20 and 22—23. Strips 11 and 12 define part of hole 117 through which the stay bolt 30 passes. Strips 11 and 12 are identical in form and construction with strip 27 and its mating strip.

As shown in Fig. 2, the tank 1 is provided with inwardly projecting flange 118 which extends around the entire inner wall of the tank and upon which the tank top 2 rests. Space 119 between the inner wall of the tank and the edge of the tank top is filled with a suitable packing 120 to prevent gas leakage. The spaces such as 53 and 107 around electrode terminals are similarly packed.

It will of course be understood that the construction which I have described with reference to a particular positive and a particular negative electrode is repeated throughout the entire cell top. Within the preferred embodiment of the invention at least alternate strips of the cover are of insulating material and preferably a material formed by the controlled polymerization of a material selected from the group consisting of butadiene and styrene.

The foregoing description is for purposes of illustration and not of limitation and it is therefore my intention that the invention be limited only by the appended claims or the equivalents thereof wherein I have endeavored to claim broadly all inherent novelty.

I claim:

1. In an electrolytic cell of the tank type, the improvement comprising a cover composed of a plurality of first and alternate second pairs of strips having substantially parallel vertical sides, means complementarily defined by the inner strip sides of each of said pairs of strips to form an aperture, an electrode for each of said pairs of strips and having a terminal extending through said aperture, means for each electrode securing the same in substantially vertically dependant position to its pair of strips in spaced relation thereto, a diaphragm for each alternate electrode substantially surrounding the same and secured to its pair of strips in substantially vertically de-

pendant position, means within said strips collectively defining substantially horizontally extending separate first and second gas ducts, each substantially traversing all of said pairs of strips, means complementarily defined by the inner strip sides of each first pair of strips to form a gas inlet from the space above its electrode to said first gas duct, and means complementarily defined by the inner strip sides of each alternate second pair of strips to form a gas inlet from the space above its electrode to said second gas duct.

2. The improvement in accordance with claim 1 in which additionally means are complementarily defined by the inner strip sides of each of said pairs of strips to form suspension bolt apertures and in which said electrode securing means are suspension bolts extending through said last mentioned apertures.

3. The improvement in accordance with claim 20 1 in which each said diaphragm is secured by a diaphragm support comprising a sleeve of sheet metal depending from its alternate pair of strips.

4. The improvement in accordance with claim 25 1 in which each said diaphragm is secured by a diaphragm support comprising a sleeve of sheet metal depending from its alternate pair of strips provided with two flat upstanding wings interposed between one of its pair of strips and its adjacent other strip.

5. Improvement in accordance with claim 4 in which at least alternate strips are of insulating material.

6. Improvement in accordance with claim 5 in which said alternate strips are composed of 35 a material formed by the controlled polymerization of a material selected from the group consisting of butadiene and styrene.

DONALD W. KENT.
